UNITED STATES PATENT OFFICE.

HENRY F. SAWYER, OF PROVIDENCE, RHODE ISLAND.

AX-HELVE WEDGE.

SPECIFICATION forming part of Letters Patent No. 338,193, dated March 16, 1886.

Application filed October 17, 1885. Serial No. 180,164. (No model.)

To all whom it may concern:

Be it known that I, HENRY F. SAWYER, of Providence, in the county of Providence and State of Rhode Island, have invented a new and Improved Ax-Helve Wedge, of which the following is a full, clear, and exact description.

My invention relates to wedges adapted for fastening the heads of axes, hammers, hatchets, adzes, or other tools to their helves or handles, and has for its object to provide a more reliable fastening for the tool-heads than is afforded by wedges of other construction.

15 The invention consists in certain novel features of construction of the wedge, all as hereinafter fully described and claimed.

Reference is to be had to the accompanying drawings, forming part of this specification, in 20 which similar letters of reference indicate corresponding parts in all the figures.

Figure 1 is a sectional elevation of an ax or hatchet with the helve held to its head by my improved wedge, which is shown in side elevation. Fig. 2 is a side elevation of the wedge in modified form or with the lower ends of 25 its two prongs connected. Fig. 3 is an end view of the wedge shown in Fig. 1, and Fig. 4 is a central cross-sectional elevation of the 30 wedge.

The letter A indicates the improved wedge, which is to be driven into the end of the helve or handle B after the ax, hatchet, adze, or other tool head C has been placed on the 35 helve, and a screw, D, then is passed through a hole, a', in the head a of the wedge, and is screwed into the helve, all as clearly shown in Fig. 1. The head of the wedge is preferably large enough to lap upon the tool-head 40 around its eye which receives the helve.

I make the wedge A with the two longitudinally-ranging wedge-like prongs E E, which are tapered flatwise to a point, and which may be connected at their ends or points by 45 the pointed cross-bar e, as shown in Fig. 2. The prongs E E are separated sufficiently at their inner edges to give space for the passage between them of the screw D. Each of

the prongs E has formed upon its opposite sides or faces a tapering wedge-like rib, F. 50

At the under side or face of the wedge-head a, and at opposite sides of its aperture a', are formed the wedge-like lips a² a², which will drive easily into the end of the ax-helve, and will strengthen the head of the wedge A 55 around the aperture a', so as to prevent breaking of the head by the force of the blows which drive it into the helve, and the lips a² will be especially useful when the ends of the prongs E E are not connected by the tie-bar e.

It is evident that while the laterally-tapering wedge-prongs E spread the end of the ax-helve sidewise to fill the eye of the ax or other tool head transversely of the eye, the 65 longitudinally-tapering wedge-like rib F on the prongs E will spread the end of the ax-helve the other way or lengthwise of the eye of the tool to fill the eye lengthwise; hence the wedge has a splitting and wedging action 70 on the helve both ways to cause the end of the helve to tightly fit the eye of the tool all around and make a much more secure fastening for the tool-head on the handle than would a wedge acting only to spread the helve 75 laterally in the eye, as it is obvious that when the helve does not snugly fit the ends of the eye the pressure or leverage commonly applied to the helve to release the ax or tool head when it sticks or binds in the cut very 80 quickly loosens the helve to such an extent as greatly to interfere with the effective use of the tool.

When the screw D is removed, the wedge A may easily be pried from the end of the 85 helve to allow renewal of either the helve or tool-head, as may be required.

Having thus described my invention, I claim as new and desire to secure by Letters Patent—

1. A helve-wedge consisting of the head a, 90 having a cruciform wedge at each end of its under face, the long arms of said wedges being in alignment and extending in the direction of the length of the head, substantially as set forth.

2. A helve-wedge consisting of the head a,

provided on its under face with two cruciform wedges, the long arms of said wedges extending in the direction of the length of the head and connected at their adjacent ends by the pointed tie-bar *e*, substantially as set forth.

3. A helve-wedge consisting of the head *a*, provided on its under face with two cruci-

form wedges having their long arms in alignment, and the short lips on the head at opposite sides of the adjacent ends of the said long arms, substantially as set forth.

HENRY F. SAWYER.
